CLAIM

The ornamental design for a wearable injector as shown and described.

DESCRIPTION

1. Wearable Injector

FIG. 1.1 is a perspective view of a wearable injector showing the new design;
FIG. 1.2 is a top view thereof,
FIG. 1.3 is a bottom view thereof,
FIG. 1.4 is a front view thereof;
FIG. 1.5 is a back view thereof;
FIG. 1.6 is a left-side view thereof, and
FIG. 1.7 is right-side view thereof.

(Continued)

The broken lines illustrate portions of the product that form no part of the claimed designs.
